UNITED STATES PATENT OFFICE.

DANIEL E. FRANCIS, OF WATERBURY, CONNECTICUT, ASSIGNEE TO THE WATERBURY TOOL COMPANY, OF WATERBURY, CONNECTICUT, A CORPORATION OF CONNECTICUT.

REMOTE CONTROL FOR ROLLING-MILL SCREW DOWNS.

Application filed June 21, 1927. Serial No. 200,356.

This invention relates to remote controls for rolling mills. In the operation of rolling mills, such as are used for rolling steel to form rods, sheets, etc., it is of the utmost importance that the distances between the rolls be adjusted with great accuracy, in order that the final product of the rolling will be of the proper dimensions, the permissible variations from the desired dimensions being in many cases but only a few thousandths of an inch. In order to secure such great accuracy, the adjusting screws with which the mills are usually provided and by means of which the gap between the rollers is changed, must frequently be moved as circumstances dictate. Owing to the intense heat, it is not feasible for the operator of the mill to change the position of the roll adjusting screws directly at the mill. Consequently, it is the usual practice to employ some form of a remote control for adjusting such screws. Heretofore, it has been the common practice to employ an electric motor for operating the screws, the operation of which motor is controlled by an electric switch located at any convenient point sufficiently distant from the mill, suitable gearing being imposed between the electric motor and adjusting screws. One of the difficulties of the electric drives as just described is due to the tendency of the electric motors to overrun, after the control switch is opened to stop the motor, and therefore it is exceedingly difficult to adjust the rolls with the great precision and accuracy required.

The principal object of this invention is to provide a new and improved construction for a remote controlled driving gear especially adapted for rolling mills, by means of which the adjusting screws of the mills can be readily adjusted with great accuracy by the simple manipulation of a single control member.

The above and other objects will appear more fully from the following more detailed description and by reference to the accompanying drawings forming a part hereof, and wherein Fig. 1 is a somewhat diagrammatic front elevation of a rolling mill equipped with a driving gear, constructed in accordance with the principles of my invention; Fig. 2 is an enlarged front elevation of the driving gear shown in Fig. 1, a part thereof being in section; and Figs. 3

and 4 are respectively an end view and a plan of the structure shown in Fig. 2.

As shown in the drawings, the rolling mill which is indicated generally by the reference character 10 is provided with the upper 60 and lower rolls 11 and 12 respectively, the upper rolls being movable towards and from the lower rolls by means of adjusting screws in accordance with the usual construction of devices of this character. The adjusting 65 screws have connected thereto by suitable gearing a transverse shaft 16, the construction being such that rotation of the shaft produces an equal movement of the adjusting screws in the same direction, according 70 to the direction in which the shaft 16 is rotated. The shafts of the rolls 11 and 12 are driven by any suitable means such as an electric motor and suitable gearing which may be mounted within the housing indicated by the numeral 17. As the construction of the driving means for the rolls 11 and 12, and the adjusting screws by means of which the gap between said rolls is varied 75 forms no part of the present invention, the 80 constructional details of these parts have not been shown in the drawings. For the purpose of the present application it is sufficient to state that the rolling mill may be of any well-known construction. 85

Mounted on the top of the housing 17 is a hydraulic speed gear which may be of the type disclosed in Letters Patent of the United States granted to Harvey D. Williams No. 925,148, June 15, 1909. As this 90 type of hydraulic gear is well known, it is not believed necessary to illustrate the same fully in the drawings, therefore, I have shown the hydraulic variable speed gear diagrammatically as indicated generally by 95 the reference character 18.

As described more fully in the patent to Williams above referred to, this type of hydraulic gear consists of a pump or an A-end, as it is usually called, and a B-end. The 100 A-end is provided with a driving shaft 19 to which an electric motor or other suitable driving means may be connected and which shaft has secured thereto a rotary barrel having a plurality of cylinders, parallel with the driving shaft and in which reciprocate pistons. Said pistons are connected with a swash plate, the angle of inclination of which may be varied to vary the stroke of the pistons, and therefore, the output, or 110

the amount of fluid delivered by the pump, for each revolution of the cylinder barrel; the angle of inclination of the swash plate preferably being adjusted by a controlling member 20, operatively connected with a tilting box in which the swash plate is rotatably mounted. When the tilting box and swash plate are perpendicular to the driving shaft, or in "neutral position", the pistons 5 have no stroke and no fluid is pumped. As the control member is operated to tilt the swash plate, the stroke of the pistons and consequently the output of the pump is increased proportionately to the increase of 10 the angle of inclination. The inclination of the swash plate in opposite directions from the neutral position causes the pump to circulate the fluid in opposite directions, and as a result produces rotation of the B-end 15 or motor in reverse directions. The B-end or motor is similar in construction to the pump or A-end, with the exception that the swash plate of the motor is not adjustable, but is held at a fixed angle of inclination. 20 In the drawings I have indicated the A-end of the hydraulic gear by the reference character A and the B-end or motor by the reference character B. The shaft 19 of the pump A is driven to cause the pump to deliver fluid, which fluid passes to the motor B, produces reciprocation of the pistons of the motor, and causes the shaft 21 of the motor to be rotated, all as described more 25 fully in the Williams patent.

30 In the constructional example of the installation disclosed in Figs. 1 to 4, the variable hydraulic speed gear 18, consisting of a pump A and motor B, constructed as a unitary assemblage, is suitably secured to the gear housing 17 and the shaft 21 of the motor B is connected by means of a coupling 22 and reduction gearing 23 with the transverse shaft 16, the latter as heretofore described being connected by suitable gearing 35 to the adjusting screws of the rolling mill 10.

35 In order that the adjusting screws 13 of the rolling mill may be rotated as desired, from a distant control, the following means are provided: Secured to a platform or 40 bracket bolted to the top of the hydraulic gear 18 is a small electric motor 24 under control of a switch 24^a located at any suitable point at a distance from the mill. Upon the armature shaft 25 of the motor 45 24 is secured a worm 26 which meshes with a worm wheel 27 fixed upon a follow-up shaft 28, the latter being supported in suitable bearings in the brackets 29, 30, also bolted to the top of the hydraulic gear 18.

50 In the particular example illustrated in the drawing, the shaft 28, which extends horizontally and in parallelism with the transverse shaft 16, is screw-threaded for a portion of its length, as indicated by the reference character 31. The screw threaded

portion 31 of the follow-up shaft is engaged within a nut 32, keyed to a sleeve 32^a, the latter being rotatably mounted within the bracket 29. The sleeve 32^a projects outwardly beyond one side of the bracket and has secured to said projecting end a sprocket wheel 33. Trained about the sprocket wheel 33 and a sprocket wheel 34, secured to the shaft 21 of the motor B, is a sprocket chain 35 for causing the nut 33 to be rotated by the rotation of the motor shaft.

The controlling member 20 of the speed gear shown in Figs. 1 to 4 is of the type which is reciprocated to change the inclination of the swash plate of the pump A. The upper end of the control shaft 20 has connected thereto a reciprocating rod 36, the lower end of which is suitably secured to the controlling member and the upper end of which slides through a bearing 37 bolted to the bracket 30. Pivotal secured to the reciprocating rod 36, as by the bolt 38, is the yoked end 39, provided at the extremity of one arm of a bell crank 40. The bell crank 40 is pivotally mounted as at 41 in the bracket 30 and its other arm 42 extends downwardly and terminates within a slot provided in the follow-up shaft 28.

It will be understood that rotation of the follow-up shaft 28, by means of the electric motor 24 will, by the engagement of the threaded portion 31 of said follow-up shaft with the threads of the nut 32, cause the shaft 28 to be moved longitudinally of its axis, according to the direction in which it has been rotated by the electric motor 24. This movement of the follow-up shaft will cause the controlling member 20 to be moved upwardly or downwardly, as the case may be, to vary the inclination of the tilting box and swash plate of the pump A. As the driving shaft 19 of the pump is being rotated at a constant speed, the inclination of its swash plate will cause the pump to deliver fluid under pressure to the motor B, thus causing the driving shaft 21 of the motor to be rotated, and through the reduction gearing 23 and transverse shaft 16, producing rotation of the adjusting screws 13 of the mill. The rotation of the driving shaft 21 of the motor B is communicated through the reduction gearing, consisting of the sprockets 33, 34 and chain 35, to the nut 32. The arrangement of the parts is such that the nut 32 will be rotated in the same direction as the rotation of the follow-up shaft by the motor 24 as described above. This rotation of the nut 32 in the same direction as the control shaft 28 will obviously cause the follow-up shaft 28 to be moved longitudinally in a direction opposite to that produced by the rotation of the shaft by means of the electric motor 24, so that the follow-up shaft will be returned to its initial position. This longitudinal movement

of the follow-up shaft in returning to its initial position will be communicated through the bell crank 40, 42 and reciprocating rod 36 to the controlling member 20, 5 thus returning the swash plate of the pump to its neutral position. The rotation of the nut 32 is in the nature of an overhauling movement of the parts, so that the reverse movement produced by the rotation of the nut upon the follow-up shaft, will lag behind the movement of said shaft produced by the rotation of the motor 24. As long as the operator at his remote station holds in the switch which starts the electric motor 24, 10 the electric motor obviously will continue to run and the stroke of the pump will continue to be increased, but at a relatively slow rate of speed, because of the overhauling action of the nut 32. It will be obvious that as the stroke of the pump increases, the speed of the hydraulic motor B will increase and therefore the speed of rotation of the control nut will be increased. This increase in speed of the nut 32 will 15 continue until a point is reached where the speed of the nut and the speed of the follow-up shaft 28 will be the same; at this point there will be no further increase in stroke on the A-end, and consequently the speed of the shaft 21 of the B-end will remain constant. The speed attained by the B-end shaft before this point is reached obviously will be determined by the ratios of the various gears, and also obviously there 20 will be a time interval or lag before the rotation of the nut 32 reaches the speed of rotation of the follow-up shaft 28. As soon as the operator of the distant control breaks the circuit to the electric motor 24, the motor will stop, and the follow-up control 25 will bring the controlling member 20 back to neutral, thereby stopping further delivery of fluid to the motor B, and consequently stopping the rotation of the shaft 21 of said motor. As the relative movement of the adjusting screws 13 of the mill must be very small, the gear ratios are relatively small and the movement of the B-end shaft, after the motor has stopped, is only a fraction of 30 a turn. With an installation such as disclosed in this application it is possible for the operator to hold the control switch closed until the indicator device, such as is usually provided in distant controls of this 35 character, has indicated that the rolls have reached the desired setting; if then the operator breaks the circuit, travel of the adjusting screws stops practically instantaneously and there is no over travel such as occurs 40 with the electric drives heretofore commonly used.

The principles of the invention obviously are not limited in their application to the specific details of the constructional example selected for illustration, as obviously

many changes, variations and modifications of said details may be resorted to without departing from such principles.

I claim:

1. The combination with a rolling mill 70 having co-operating rolls and adjusting screws to vary the gap between said rolls, of a variable speed transmission gear including a pump and motor, the latter having a rotatable driving shaft, gearing connecting 75 said shaft and said screws, said pump having adjustable means to reverse or vary the output thereof and thereby cause the speed or direction of rotation of said motor to be varied, an electric motor for actuating said 80 adjustable means, and means driven by said rotatable driving shaft to cause said adjustable means automatically to be moved in a direction opposite to that produced by said electric motor.

2. The combination with a rolling mill 85 having co-operating rolls and adjusting screws to vary the gap between said rolls, of a variable speed transmission gear including a pump and motor, the latter having a 90 rotatable driving shaft, gearing connecting said shaft and said screws, said pump having adjustable means to reverse or vary the output thereof and thereby cause the speed or direction of rotation of said motor to be 95 varied, an electric motor for actuating said adjustable means, and a follow-up device operatively associated with said rotatable driving shaft and connected with said adjustable means for automatically producing 100 a movement of said adjustable means equal to, and opposite in direction to, that produced by said electric motor, the movement of said adjustable means produced by said follow-up device lagging behind the movement produced by said motor.

3. The combination with a rolling mill 105 having co-operating rolls and adjusting screws to vary the gap between said rolls, of a variable speed transmission gear including a pump and motor, the latter having a 110 rotatable driving shaft, gearing connecting between said shaft and said screws, said pump having adjustable means to reverse or vary the output thereof and thereby cause 115 the speed or direction of rotation of said motor to be varied, an electric motor for actuating said adjustable means, a distant control for said electric motor, a follow-up device connected with said adjustable means, 120 and driving means from said rotatable shaft to said follow-up means for producing a movement through said follow-up device of said adjustable means opposite in direction to that produced by said electric motor, the 125 movement of said adjustable means produced by said follow-up device lagging behind the movement produced by said electric motor.

4. The combination with a rolling mill 130

having co-operating rolls and adjusting screws to vary the gap between said rolls, of a variable speed hydraulic transmission gear comprising a pump and a motor, the latter having a rotatable driving shaft, gearing connecting said shaft and screws, said pump having an adjustable control means for reversing or varying its output thereby to cause the speed or direction of rotation of said motor to be varied, said means including a pair of rotatable members in screw threaded engagement, an electric motor for driving one of said members, a distant control for said electric motor, and driving connections between said rotatable shaft and the other of said members for causing the rotation of said shaft to produce a follow-up movement between said two members.

5. The combination with a rolling mill having co-operating rolls and adjusting screws to vary the gap between said rolls, of a variable speed hydraulic transmission gear comprising a pump and a motor, the latter having a rotatable driving shaft, gearing connecting said shaft and screws, said pump having an adjustable control means for reversing or varying its output thereby to cause the speed or direction of rotation of said motor to be varied, said means including 20 a pair of rotatable members in screws threaded engagement, an electric motor for driving one of said members, a distant control for said electric motor, and driving connections between said rotatable shaft and the other of said members for causing the rotation of said shaft to produce a follow-up movement between said two members.

6. The combination with a rolling mill having co-operating rolls and adjusting screws to vary the gap between said rolls, of a variable speed hydraulic transmission gear comprising a pump and a motor, the latter having a rotatable driving shaft, gearing connecting said shaft and screws, said pump having an adjustable control means for reversing or varying its output thereby to cause the speed or direction of rotation of said motor to be varied, said means including a pair of rotatable members in screw threaded engagement, an electric motor for driving one of said members and producing a movement of said adjusting means to vary or reverse the rotation of said hydraulic motor and its rotatable shaft, a distant control for said electric motor, a driving connection between said rotatable shaft and the other of said rotatable members for producing a movement of said other member in the same direction as that of said one member produced by the rotation of said electric motor thereby to neutralize the movement of said adjusting means produced by said electric motor, the neutralizing effect produced by said other member lagging behind the movement produced by said electric motor.

In testimony whereof I have hereunto set my hand.

DANIEL R. FRANCIS.
